Patented Mar. 14, 1916.

Inventor
LOUIS J. FLEMAL

By *Watson E. Coleman*

Attorney

UNITED STATES PATENT OFFICE.

LOUIS J. FLEMAL, OF LORAIN, WISCONSIN.

SCRAPER.

1,175,512.

Specification of Letters Patent. Patented Mar. 14, 1916.

Application filed November 18, 1915. Serial No. 61,362.

To all whom it may concern:

Be it known that I, LOUIS J. FLEMAL, a citizen of the United States, residing at Lorain, in the county of Polk and State of Wisconsin, have invented certain new and useful Improvements in Scrapers, of which the following is a specification, reference being had to the accompanying drawings.

This invention relates to certain improvements in scrapers and has relation more particularly to a device especially designed for use in connection with shelving or the like; and it is an object of the invention to provide a scraper of novel and improved construction and comprising a plurality of blades which may be readily and conveniently maintained in operative relation and which may be independently removed and replaced as the necessities of practice may require.

The invention consists in the details of construction and in the combination and arrangement of the several parts of my improved scraper whereby certain important advantages are attained and the device is rendered simpler, less expensive and otherwise more convenient and advantageous for use, all as will be hereinafter more fully set forth.

50 The novel features of the invention will be carefully defined in the appended claim.

In order that my invention may be the better understood, I will now proceed to describe the same with reference to the accompanying drawings, wherein—

Figure 1 is a longitudinal vertical sectional view taken through a scraper constructed in accordance with an embodiment of my invention, a portion of the handle member being in elevation; Fig. 2 is a sectional view taken substantially on the line 2—2 of Fig. 1, looking in the direction of the arrow; Fig. 3 is a sectional view taken substantially on the line 3—3 of Fig. 1, looking in the direction of the arrow; Fig. 4 is a fragmentary view in perspective illustrating in detail the interlock between a blade and an assembling bar; and Fig. 5 is a fragmentary view in perspective illustrating one of the locking bolts coacting with the handle member, portions of the scraping blade and assembling bar being indicated in fragment by dotted lines.

As disclosed in the accompanying drawings, 1—1 denote a plurality of assembling bars and 2—2 a predetermined number of

scraping blades, said bars 1 and blades 2 being perpendicularly related when in operative relation and, as particularly illustrated in Fig. 4, it is to be observed that each of the blades 2 has provided in its upper margins a transversely disposed open slot 3 and the lower margin of each of the assembling bars 1 is provided with a transversely disposed open slot 4 whereby said 60 blade and bar may be readily and effectively interlocked. It will also be readily observed that by this manner of assembling the bars and blades, a single blade may be readily removed or replaced independently 65 of the other especially when it is desired to sharpen the cutting edge of the scraping blade. It is also to be noted that the blades 2 are of such width as to extend below the assembling bar 1 when in applied position. 70

5 denotes a plate having depending from its longitudinal margins the flanges 6 having produced therein the open slots 7 so that said flanges may interlock with the intermediate assembling bars 1. The opposite 80 ends of the plate 5 has extending upwardly therefrom the arms 8 between which is arranged the hand grasp 9, said hand grasp 9 being secured in any preferred manner to the upper or free extremities of the arms 8. 85 The plate 5 is provided with the longitudinally disposed slots 10 through which the threaded shank 11 is adapted to extend, the lower end of each of said shanks 11 being provided with an angular extension 12 terminating in the head 14. The angular portion 12 is adapted to be engaged within a widened slot 4^a in an adjacent assembling bar 5 and the upper end of the shank 3 is engaged by the clamping nut 15 whereby it 90 will be perceived that the plate 5 may be readily and effectively clamped in applied position. I find it in practice best to impose upon the plate 5 the supplemental plate 16 provided with the openings 17 through 95 which the threaded shanks 11 extend and with which the clamping nuts 5 contact.

As is particularly illustrated in Fig. 5, it is to be noted that one side of a head 14 is flattened, as at 18, to permit the shank 11 105 to be positioned immediately adjacent and in contact with the coacting assembling bar 1.

From the foregoing description, it is thought to be obvious that a scraper constructed in accordance with my invention is 110 of an extremely simple and comparatively

inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

A scraper comprising a plurality of assembling bars, a plurality of scraping blades

arranged transversely of and interlocked with the assembling bars, a plate provided with depending flanges adapted to interlock with certain of the assembling bars, a hand grasp operatively connected to the plate, and 20 clamping members coacting with the plate and certain of the assembling bars for maintaining the plate in applied position.

In testimony whereof I hereunto affix my signature in the presence of two witnesses. 25

LOUIS J. FLEMAL.
